UNITED STATES PATENT OFFICE

102,022

DESIGN FOR A SHOWCASE

Peter Wilson, Berkeley, Calif.

Application July 29, 1936, Serial No. 64,118

Term of patent 7 years

To all whom it may concern:

Be it known that I, Peter Wilson, a citizen of the United States, residing at Berkeley, in the county of Alameda and State of California, have invented a new, original, and ornamental Design for a Showcase, of which the following is a specification, reference being had to the accompanying drawing, forming part thereof.

The figure is a perspective view of a showcase showing my design.

I claim:

The ornamental design for a showcase, substantially as shown.

PETER WILSON.
